(57) CLAIM

The ornamental design for a three-sided LED light, as shown and described.

DESCRIPTION

FIG. 1 is a perspective view of one preferred embodiment of a three-sided LED light incorporating my design;

FIG. 2 is a front elevational view of the light of FIG. 1;

FIG. 3 is a rear elevational view of the light of FIG. 1;

FIG. 4 is a top plan view of the light of FIG. 1;

FIG. 5 is a bottom plan view of the light of FIG. 1;

FIG. 6 is a right side elevational view of the light of FIG. 1, the left side elevational view being a mirror image of the right side elevational view;

FIG. 7 is a perspective view of another preferred embodiment of a three-sided LED light incorporating my design;

FIG. 8 is a front elevational view of the light of FIG. 7;

FIG. 9 is a rear elevational view of the light of FIG. 7;

FIG. 10 is a top plan view of the light of FIG. 7;

FIG. 11 is a bottom plan view of the light of FIG. 7; and,

FIG. 12 is a right elevational view of the light of FIG. 7, the left side elevational view being a mirror image of the right side elevational view.
